UNITED STATES PATENT OFFICE.

DANIEL J. GOLDEN, OF BROCKTON, MASSACHUSETTS.

RUNNING-SHOE.

1,333,409.

Specification of Letters Patent.

Patented Mar. 9, 1920.

Application filed September 29, 1919. Serial No. 327,171.

To all whom it may concern:

Be it known that I, DANIEL J. GOLDEN, a citizen of the United States, residing at Brockton, in the county of Plymouth and 5 State of Massachusetts, have invented new and useful Improvements in Running-Shoes, of which the following is a specification.

This invention relates to shoes worn by 10 contestants in athletic running contests, the tread face of the fore part of the shoe being provided with sharp spurs or spikes of considerable length, standing perpendicular to the tread face.

15 The invention has for its object to provide an improved spike attachment for a shoe of this character, and is embodied in the improvements which I will now proceed to describe and claim.

20 Of the accompanying drawings forming a part of this specification,—

Figure 1 is a bottom view of a running shoe embodying the invention.

Fig. 2 is a section on line 2—2 of Fig. 1.

25 Fig. 3 is a section on line 3—3 of Fig. 1.

Fig. 4 is a side view of one of the spurs.

The same reference characters indicate the same parts in all of the figures.

In the drawings, 12 represents a thin 30 resilient sheet metal plate, preferably of sheet steel, formed to cover a portion of the tread face of a flexible running shoe sole 13, the outer side of said plate constituting a part of the tread face. The plate is perforated

35 at suitable intervals to receive rivets 14, whereby it is attached to the sole, the rivets being preferably of the well known tubular form, and having headed outer ends seated on the outer surface of the plate, and upset 40 inner ends seated on the inner surface of the sole 13, as shown by Fig. 3.

The plate 12 constitutes a base supporting a plurality of spikes or spurs 15, which are substantially perpendicular to the plate.

45 Each spike has a head 16, provided with a flat side 16^a seated on the plate 12, and a crowning side 16^b, forming an annular crowning tread face portion merging into the tread face of the plate 12, the margin of 50 the head being reduced to a thin edge,

The heads 16 are securely attached to the plate 12, preferably by rivets 17, inserted in holes formed for their reception in the plate and the spike heads, said rivets being preferably of the ordinary bifurcated type, 55 and having heads bearing on the inner side of the plate 12, and upset ends bearing on the inner side of the plate 12, and upset ends bearing on the crowning sides of the rivets and conforming to the inclination of 60 side sides, as shown by Fig. 2.

It will now be seen that the resilient plate 12 attached to the sole, and the spurs having the heads formed as described, and attached to the plate, constitute a simple, strong, and effective attachment to a sole of a running shoe, the heads 16 having bearings of large area on the plate, and the crowning sides of the heads forming annular crowning tread portions merging into the tread face 65 plate, there being no angles or corners in which mud or dirt is liable to lodge. The sole 13 and plate 12 are simultaneously flexed by the action of the foot in running. 70

I claim:

A running shoe having a flexible sole and a spike attachment comprising a thin resilient sheet metal plate bearing on the tread face of the sole and attached thereto, a plurality of spikes or spurs, each having a head 80 provided with a flat side, seated on the plate, and a crowning side forming an annular crowning tread face portion surrounding the spike and merging into the tread face of the plate, so that the head is reduced to a thin 85 edge at its margin, attaching rivets inserted in holes formed for their reception in the plate and spike heads, said rivets having heads seated on the inner surface of the plate and upset ends seated on the crowning 90 sides of the spur heads and conforming to the inclination of said sides, the plate and sole being adapted to be simultaneously flexed. 95

In testimony whereof I have affixed my signature.

DANIEL J. GOLDEN.
